UNITED STATES PATENT OFFICE.

BERNE NADALL, OF KINGSTON-UPON-THAMES, ENGLAND, ASSIGNOR TO THE LINOTYPE COMPANY, LIMITED, OF LONDON, ENGLAND.

DESIGN FOR A FONT OF TYPE ORNAMENTS.

SPECIFICATION forming part of Design No. 35,887, dated April 29, 1902.

Application filed January 26, 1902. Serial No. 91,293. Term of patent 14 years.

To all whom it may concern:

Be it known that I, BERNE NADALL, a citizen of the United States, residing at Kingston-upon-Thames, in the county of Surrey, England, have invented and produced a new and original Design for a Font of Type Ornaments, of which the following is a specification.

My design is clearly shown in the accompanying typographical impressions, the type composing the font being numbered 1, 2, 3, and 4.

Referring particularly to the form numbered 1, it will be seen to present in outline a conventional illustration of a leaf having its stem bent to form a border or inclosure about its body. The leaf-like form, which is represented by a single fine line, is substantially square in form, and the stem-like border is formed by two fine parallel lines. In the form numbered 1 this stem representation is connected with the leaf-like body at the lower left-hand corner thereof, while in form numbered 2 it is connected with the lower right-hand corner of said body—that is, the forms numbered 1 and 2 are each the reverse of the other.

Form numbered 3 includes two series of irregular-shaped forms arranged in parallel lines, a serpentine-like coil arranged at one

end of said series of forms and formed of two parallel lines and two parallel lines arranged at the opposite end of said series of forms. The intermediate series of irregular forms are outlined only by fine lines.

35

The forms numbered 3 and 4 differ from each other in the same respect as form numbered 1 differs from that numbered 2—that is, form numbered 4 is the reverse of that numbered 3.

40

The forms numbered 3 and 4 are of the same height as those numbered 1 and 2, so that when any two or more of said forms are assembled the top and bottom lines thereof will register.

45

The several type ornaments herein described are adapted to be grouped in various ways to form borders and other composite typographic ornaments.

Having thus described my invention, what I claim as new, and desire to secure by Letters Patent, is—

The design for a font of type ornaments, substantially as herein shown and described.

In testimony whereof I affix my signature in presence of two witnesses.

BERNE NADALL.
